UNITED STATES PATENT OFFICE.

INRANK A. PACKARD AND JOHN D. STRUBLE, OF SALINA, KANSAS.

SOAP.

SPECIFICATION forming part of Letters Patent No. 394,289, dated December 11, 1888.

Application filed April 10, 1888. Serial No. 270,209. (Specimens.)

To all whom it may concern:

Be it known that we, INRANK A. PACKARD and JOHN D. STRUBLE, of Salina, in the county of Saline and State of Kansas, have invented 5 a new and Improved Soap Compound, of which the following is a full, clear, and exact description.

Our invention relates to a composition of matter adapted for use in connection with 10 soap, especially laundry-soap, and has for its object to provide an article by the use of which all bleaching liquids or powders and acids may be dispensed with, and which, when used for laundry purposes, will effectu- 15 ally clean and whiten the most delicate fabrics—such as silk, satin, and fine laces—with- out the slightest injury thereto.

The composition consists of the following ingredients, combined in substantially the fol- 20 lowing proportions, viz: Equal parts of aqua- ammonia, spirits of camphor, spirits of niter, and ether.

The above articles readily cut each other

and are mixed until they thoroughly com- 25 mingle.

When soap of any description is in process of manufacture, a suitable quantity of the compound is incorporated, the amount being determined by the experience of the operator and the proposed character of the soap. 30

For laundry-soap we usually employ eight ounces of the compound for every two hundred and fifty pounds of soap.

Having thus described our invention, what we claim as new, and desire to secure by Letters Patent, is—

The herein-described composition of matter for laundry purposes, consisting of a saponaceous material, aqua-ammonia, spirits of camphor, spirits of niter, and ether, in sub- 40 stantially the proportions specified.

INRANK A. PACKARD.
JOHN D. STRUBLE.
